UNITED STATES PATENT OFFICE.

JOHN ALBERT SWORBEL, OF ATTLEBORO, MASSACHUSETTS, ASSIGNOR TO McRAE AND KEELER, OF ATTLEBORO, MASSACHUSETTS, A FIRM.

DESIGN FOR A MEDALLION.

No. 39,954.

Specification for Design.

Patented May 4, 1909.

Application filed February 15, 1909. Serial No. 478,133. Term of patent 3½ years.

To all whom it may concern:

Be it known that I, JOHN ALBERT SWORBEL, a citizen of the United States, residing at Attleboro, in the county of Bristol and State of Massachusetts, have invented a new, original, and ornamental Design for a Medallion, reference being had to the accompanying drawing.

The drawing represents a view of the obverse side, showing my design.

I claim—

The ornamental design for a medallion, as shown.

JOHN ALBERT SWORBEL.
